DECORATIVE LAMINATED SAFETY
STRUCTURE

Victor H. Rosén, Chicago, Ill.

Application May 24, 1937, Serial No. 144,354

2 Claims. (Cl. 41—22)

The present invention relates to a decorative safety structure and has particular reference to glass laminated to steel for use in buildings, signs, furniture and the like.

Colored and decorative glass and other frangible materials are being used today for the exterior decoration of buildings and for many interior decorative purposes. When used on building exteriors the frangible materials are normally cut and shaped into panels that are applied directly to the masonry with an intervening binding agent of cement or mortar to hold them in place. Oftentimes this decorative theme is carried to some heights above streets and sidewalks. Because of this positioning of the material there is a likelihood of breakage due to shocks or temperature changes causing the frangible material to shatter or break and fall to the ground. Besides the spoiling of the decorative theme, there is the danger of injury to people and objects struck by the falling fragments.

A principal object of the present invention is to provide a decorative material that is durable, inexpensive and simple to manufacture.

A further object of this invention is to provide a material made at least in part from glass or frangible materials that will not shatter even though broken.

A still further object of this invention is to provide a decorative material that may be attached to interiors or exteriors of buildings and endure after breakage, without injury to persons or objects below.

Another object of this invention is to provide a sturdy structure partially of frangible material that is sturdy, resistant to breakage and shatter-proof.

Yet another object of my invention is to provide a decorated wall protected from wear and discoloration that is easily cleaned and maintained in its original state with little effort.

For aiding in the disclosure of the invention, I show in the accompanying drawing, forming a part of this specification, certain arrangement of parts by reference to which the article and its mounting is described. It is to be understood that the description and drawing are presented for purposes of illustration only and are not to be construed so as to limit the scope of the claims unnecessarily. The thickness of the plates or layers is exaggerated in the drawing for purposes of clarity.

In the drawing:

Fig. 1 is a view in elevation of one embodiment 55 of the structure of the invention;

Fig. 2 is a sectional view through the structure taken on the line 2—2 of Fig. 1 showing means for supporting it from a wall;

Fig. 3 is an enlarged sectional view of the structure showing a framework that may be used in connection therewith; 5

Figs. 4, 5, 6 and 7 are sectional views of different embodiments of the invention showing various uses.

In a preferred embodiment of my invention I 10 laminate a glassy or frangible material to a sturdy backing member through a proper adhering agent, so that, upon breakage of the material through some mishap, the separate pieces of the material will not shatter free from the backing 15 member but will be held in place. By means of this structure the material will resist a greater blow or force than it would standing alone. It is also prevented from undergoing substantial oscillations or vibrations which might tend to 20 break or shatter it.

This structure may be used in various embodiments depending upon the purpose of the use and the decoration desired. For instance, a highly polished sheet of metal may be laminated to 25 transparent glass through well known transparent adhering agents, such as "Fibestos." The finished structure is of the appearance of highly finished metal. The metal is protected from atmospheric conditions while the glass is rendered 30 highly resistant to breakage and prevented from shattering. Either the metal or glass may be first painted upon the inner surfaces or colored opaque glass may be used. In the last instance the metal need not be finished but may have 35 merely a coat of rust preventing paint.

Preferably, the structure is sealed at its edges to prevent moisture or other agencies from injuring or discoloring the structure between the laminated parts. 40

Tapestries or advertising media may be inserted between the frangible material and the supporting member for various decorative effects and properly held in place.

By using a backing member of sturdy, substantial 45 nonbreakable characteristics, the structure may be supported from a wall through hooks or other devices, insuring against its falling. Likelihood of injury to persons from falling pieces is thus greatly reduced over structures that must 50 rely only upon plastics for this purpose.

The final structure is practically integral and is greatly strengthened over present structures used for similar purposes and the parts cooperate in acting together to furnish an entity where each 55

part is superior in its function to that which it had alone.

As shown in the drawing, one embodiment has a body portion 10 comprising a backing member 12 preferably of metal to which is laminated a member of frangible material 14. Intervening between these two members is an adhering agent 16 somewhat exaggerated as to thickness for purposes of clarity. The metal backing member 12 may be of plated or unplated steel; monel or Alleghany metal may be used, or copper, zinc and other materials can be employed.

The frangible material may be of transparent, colored, frosted, opaque glass or marble or tile and like materials, depending upon whether the beauty of the metal is desired. Beauty of glass would not require an expensive or finished metal.

As an adhering agency, cellulose or resin products, or plastics may be used and they may be transparent or not, again depending upon their use. In practice a material called "Fibestos" has been found to give excellent results and water glass has given satisfaction in smaller sized pieces. Preferably, the frangible and supporting members are laminated by using a sufficient amount of heat and pressure to cause them to form a secure adherent bond between them.

The edges of the finished structure are sealed against moisture in ways well known in the manufacture of safety glass or a sealing frame may be used for this purpose. One sealing means 18 is shown in Figs. 2, 3 and 5 and comprises a frame of strap metal having an inwardly turned flange. This strap overlies the laminated edges and is spot-welded to the metal backing member 12, or otherwise affixed to the structure. A modification is shown in Figs. 6 and 7 where the sealing frame may be a channelled member 21 clamped around edges of the structure. It may be plated or highly polished to give a decorative trim to the complete structure.

Each of the finished structures may be secured or supported from a wall in any suitable manner. Where the backing member is of metal, hooks or eyes may be welded directly thereto and fastened to eyes or hooks embedded in a masonry wall. One means shown is to form a rearwardly extending flange 20 upon the backing member. This flange is slotted as at 22. A flattened hook member 23 is bolted to the supporting wall and the structure 10 is supported from the hook by hanging the slotted flange thereover.

Other modifications are shown in the drawing for obtaining various decorative effects.

In Fig. 4 there is shown a coating of lacquer or paint 24 applied to the backing member 12 with the frangible member 14, in this instance a transparency, laminated thereto through the intervening adhering agency 16. In Fig. 5 the paint or lacquer 24 layer is shown applied to the inner portion of the glass.

Fig. 6 shows a modification whereby a decorative fabric or paper layer 26 is laminated to the structure by means of two layers of the adhering agency 16. In use, this could be applied to signs or other advertising media. The same results of shock resistance, added strength and the prevention of shattering are accomplished in this modification.

In the same way, double-faced signs, screens or decorative devices may be built, using one common backing member 12 as shown in Fig. 7 and adding the paint layer 24, the adhering agency 16 and the frangible material 14 all laminated into an integral whole.

Because of the added strength given by the backing member 12, the frangible member may be greatly reduced in thickness and the metal 20 backing member may be of sheet-like thickness depending upon the use to which it is put. A mere gold or silver leaf or sprayed layer or deposit of a metallic nature is not sufficient for the purpose of a backing member as a blow or condition causing the breakage of the glass would cause the metal to tear or break, spoiling the structure and not obtaining the results for which this invention is adapted. The backing member should be of sufficient strength and thickness to hold the frangible material to it even after breakage of the latter to prevent shatter.

Other modifications of this invention will be obvious to those skilled in the art. Such modifications are intended to be included in the language and spirit of the appended claims.

I claim:

1. In a structural device, a sheet metal backing member, a decorative member laminated to said backing member, a transparent member laminated to said decorative member and transparent adhering agency between said members for supporting said transparent and decorative members from said backing member even after breakage.

2. In a structural device for decorating walls and the like, a plurality of separate sheet metal backing members for arrangement in contiguous relationship, frangible material laminated to and supported by each of said backing members, an intervening adhering agency holding said frangible material to its respective backing member even after breakage, and fastening means on each of said backing members, said fastening means arranged to support said backing members positively to a wall and cooperating with fastening members of contiguous backing members to form a substantially integral decorative wall.

VICTOR H. ROSEN. 60
